WILLIAM WEBSTER WILSON, OF LOS ANGELES, CALIFORNIA.

ROD ELEVATOR.

Application filed November 6, 1924. Serial No. 748,004.

This invention has to do with hoisting elevators, and although not limited thereto, it is particularly applicable to elevators for lowering and raising sucker rods of deep well pumps.

It may be stated as the general object of the invention to provide a strong, dependable elevator which is capable of quick application to and release from sucker rods, together with automatically acting means for holding the jaws releasably in either closed or open position.

The device has self-closing characteristics, that is, when the elevator is thrust upon the rods, the jaws are automatically swung to and locked in rod embracing position. Elevator application and locking are thus accomplished by a single movement on the part of the operator, that is, he need merely thrust the elevator forwardly onto the rods without performing separate jaw closing and jaw locking operations. The locking device is of such construction and so protected that there is no danger of it being accidentally released.

When it is desired to release the elevator, the operator need merely pull on an operating handle. The initial pull frees the locking device from the jaws, and continuation of the pull swings the jaws clear of the rod. When the operating handle is subsequently released, the locking device automatically moves to such a position that it yieldably retains the jaws open and ready for re-application of the elevator. When in this position, the jaws are so enclosed that they are in no danger of being swung to closed position by accidental engagement with extraneous bodies. Furthermore, with the jaws in this open position, the locking device cannot be moved in a manner to close them; so it is practically assured that the elevator is always in condition for immediate application to work. Thus it will be seen that withdrawal from one piece of work automatically places the elevator in condition for immediate application to another piece of work.

When it is considered that elevator application and automatic locking of the jaws is accomplished by movement of the elevator towards the rod, and that unlocking of the jaws and withdrawal of the elevator is accomplished by a single pull of the operating handle away from the rod, and further that the jaws are yieldably retained in open posi-

tion ready for re-application without the necessity of a separate manual operation, it will be readily understood that my device renders it possible to speed up greatly the operation of raising and lowering sucker rods.

A preferred embodiment of my invention will be fully described in the following detailed specification, reference being made to the accompanying drawings, in which:

Fig. 1 is a front elevation of my improved elevator applied to a sucker rod;

Fig. 2 is an enlarged plan view of the elevator with hoisting bail detached, the section through the sucker rods being taken at a point immediately above the elevator jaws;

Fig. 3 is a section on line 3—3 of Fig. 2, with sucker rods removed;

Fig. 4 is a view similar to Fig. 2, except that certain parts are broken away and shown in section to expose underlying parts;

Fig. 5 is a view similar to Fig. 4, but showing the position the parts assume when being applied to or withdrawn from a sucker rod; and

Fig. 6 is a detached, plan view of an elevator jaw.

First, without going into details of construction and operation, I will describe the general character and use of my elevator. Body 10 has diametrically opposed lugs or trunnions 11 to take the eyes of bail 13 by which attachment is made to the hook (not shown) of hoisting tackle arranged over the well bore.

The elevator includes jaws 12 which may be of identical construction and are adapted to be swung about vertical axes to and from positions of closure about usual sucker rod S. It is typical of a sucker rod to have a downwardly facing support shoulder 14 (which is the under face of collar 15), an upwardly extending threaded projection 16, and a portion 17 of polygonal cross section for the application of wrenching tools.

When the elevator is applied to the sucker rods as in Fig. 1, support shoulder 14 rests on top jaws 12, and the rod is lowered away until the elevator comes to rest on top of the pump casing. The elevator then serves as a supporting clamp to hold the rod suspended until a second rod is picked up by a second elevator and threadably connected to extension 16, the bail of the first elevator being first swung to one side to expose the

top of said extension. Thereupon, the line of sucker rods is lifted slightly, the first elevator disengaged from the first rod, and the line lowered under control of the second elevator. Thus the two elevators are alternately used as supporting and control members until the entire line is in. In withdrawing sucker rods for replacement or repair of pump plungers, the same operations are performed in reverse order.

It will be seen that the aggregate time consumed in attachment and detachment of the elevators amounts to a very considerable factor in the time required to lower and raise sucker rods, and I will now proceed to a detailed description of my improved invention and its operation, from which it will be evident how I reduce this time factor to a minimum, yet positively guard against accidental release of the rods—a most important feature.

Body 10 has a centrally disposed recess 18 of the horizontal configuration clearly illustrated in Figs. 4 and 5. The opposed over-hanging body portions 19 which define the top and bottom of this recess may be considered cover plates, and they may either be integral with or separable from the body member proper. Vertically aligned bores 20, preferably midway between and in line with trunnions 11, are provided in plates 19 and are preferably of a diameter to take, with clearance, sucker rod collar 15. Side entrance slots 21, preferably of only sufficient horizontal extent to pass rod S freely therethrough and therefore somewhat restricted with respect to the diameters of bores 20, open to said bores. The defining walls 22 of slot mouths 22^a preferably incline outwardly so sucker rods may be more readily guided to the slots and their communicating bores.

Jaws 12 are within recess 18 and are mounted for horizontal pivotal movement about the plate supported pins 23. Preferably these pins are in line with trunnions 11 and bores 20, and are equi-spaced from the center of body 10. The opposed faces of the jaws have rod receiving notches 24 which are preferably compleinentlytarily arcuate, and, when the jaws are swung to the rod embracing position of Fig. 4, the notches are adapted to define a circular opening of a diameter substantially equal to or slightly larger than that of the sucker rods. Jaws 12 may be considered L-shaped members, the legs 25 of which are slot-closing terminals, and the legs 26 of which are adapted to contact with the locking device, now to be described. Lock plunger 27 is adapted to slide through way 28, the axis of which is substantially perpendicular to and midway between the pivotal axes of the jaws. The plunger has collar 29 and terminates in a coaxial cone or wedge 30, though this cone is not

essential to the invention in its broader aspects. Annular shoulder 31 is adapted to engage the body wall 10^a for limiting the retractive movement of the plunger and the outer end of the plunger extends with sliding fit through bore 32 of handle or knob 33, the handle being counterbored at 34 to receive plunger head 35.

An expansive coil spring 36 encircles plunger 27 between collar 29 and wall 10^a, thus exerting a constant tendency to bias the plunger inwardly to the extended positions of Figs. 4 and 5.

The two jaws have identical shoulder arrangements, and I will describe certain relationships which exist between these various shoulders although it will be understood that it lies within the scope of my invention in its broader aspects and as set forth in certain of my claims to change certain of these relationships or even to eliminate certain of the shoulders. The end shoulders *a* of terminals 25 are adapted to engage one another to establish the closed position of the jaws (Fig. 4). Shoulders *b* of legs 26 are adapted to engage one another to establish the full open position of the jaws. I will therefore term shoulders *a* and *b* "limit shoulders" since they limit the extent of jaw oscillation. Legs 26, where they extend below line of centers C when the jaws are full open (Fig. 5) may be relieved at *b'* so they will not interlock to hold the jaws open in the event there is insufficient play between the jaws and their pins to prevent such interlocking. Now it lies within the scope of certain of my claims to provide means other than coacting shoulders on the jaws for thus limiting jaw oscillation (for instance, the jaw legs may engage the defining walls of recess 18) but the abutting shoulder arrangement just described is a preferable construction, and I will therefore describe the rest of the jaw shoulders in their association with shoulders *a* and *b*. Thrust shoulders *c* are perpendicular to limit shoulders *b* so when these limit shoulders are in engagement (Fig. 5) the under face of plunger collar 29 is thrust into engagement with shoulders *c* and yieldably retains the jaws in full open position. The angles between jaw shoulders *d* and thrust shoulders *c* are substantially equal to the exterior angle between cone 30 and collar 29 so, when the jaws are full open, shoulder *d* engages the cone face.

It will be noted that when the jaws are fully open, terminals 25 are within recess 18 and clear of slots 21 so there is no danger of the jaws being swung to closed position by engagement between said terminals and extraneous bodies.

Now assume the jaws are open and the elevator is about to be applied to sucker rod S (Fig. 4). The elevator is thrust bodily

towards the rod so the latter slips through slots 21 into the elevator bore. It will be understood that elevator application is made sufficiently low on the rods to clear rod collar 15. When the rod strikes jaw legs 26, the jaws are automatically swung to closed position about the rods. Legs 26, during initial jaw movement, thrust plunger 27 to retracted position against the action of spring 36. When the jaws are in their full closed position, as established by engagement of limit shoulders *a*, spring 36 urges the plunger inwardly until the under face of collar 29 engages thrust shoulders *e* which are perpendicular to said shoulders *a*. The angles between shoulders *b* and *e* are substantially equal to the exterior angle between cone 30 and collar 29 so the cone lies between opposite shoulders *d* in the manner illustrated in Fig. 4.

When the jaws are thus fully closed and plunger 27 fully extended, the peripheral face of collar 29 engages lock shoulders *f* (perpendicular to thrust shoulders *e* and therefore parallel to limit shoulders *a*) and prevents subsequent accidental rotation of the jaws to open position. Thus it will be seen that a single thrust of the elevator against the rod has served to close and automatically lock the jaws about the rod. The elevator may then be lifted until the tops of jaws 12 engage rod shoulder 14, rod collar 15 then lying within bore 20 of upper plate 19 to aid in preventing lateral displacement of the rod relative to the elevator.

When it is desired to detach the device, the elevator is first lowered (or the rod is raised) sufficiently to clear collar 15 from bore 20. This position is shown in Fig. 1. Then the operator pulls on handle 33 with the initial effect that plunger 27 is retracted against the action of spring 36 and collar 29 is freed from lock shoulders *f*. A continued pull on handle 33 causes engagement between plunger shoulder 31 and wall 10^a and consequently causes withdrawal of body 10 from rod S, jaws 12 swinging to open position during the lateral movement of the body 10 since pins 23 move with the body while jaw legs 25 must drag around rod S. When the elevator is entirely clear of the rod, the operator releases his hold on handle 33 with the result that spring 36 returns plunger 27 and handle 33 to the position of Fig. 5, collar 29 engaging thrust shoulder *e* to hold the jaws yieldably in open position and ready for immediate reapplication of the elevator. Cone 30 may be so proportioned and angled that, in the return of plunger 27 to extended position, it spreads jaws 12 slightly more than does rod S in its outward passage between the jaws. When the jaws are swung to closed position, cone 30 serves to pilot collar 29 positively to locking position even though there may be looseness

between way 28 and plunger 27 or in the pivotal mounting of the jaws.

In describing the application of the elevator to work, it was stated that body 10 was thrust towards the rod. Now even if the operator be grasping and thrusting against handle 33 at the time of application, the mechanism functions automatically to close and lock about the rod as described and without the exertion of back pressure on the handle. This is for the reason that when the plunger 27 is retracted by the thrust of jaws 12 it is capable of relative longitudinal movement with respect to handle 33 so said handle may be kept in contact with body 10 while plunger head 35 travels through counterbore 34. The depth of the counterbore is preferably such that head 35 does not protrude beyond the end of handle 33 at any period of plunger movement. This provision not only prevents interference between the plunger head and the operator's hand, but also prevents the exposure of the plunger to contact with tools or the derrick structure and thus protects the plunger from harm.

It will be noted that the elevator is symmetrical about its horizontal axial plane so it may be applied and operated equally well with either of plates 19 uppermost.

It will be evident from the above that various changes in design, structure and arrangement over the showing of the drawings may be made without departing from the spirit of the invention, and I wish to reserve to myself all such changes as may lie within the scope of the appended claims.

Having described a preferred form of my invention, I claim:

1. In an elevator, the combination of a body member, two opposed jaws pivotally mounted on the body member and movable on their pivotal centers to open and close the elevator whereby rods may be inserted in and withdrawn from the elevator, a plunger slidably mounted on the body member, spring means adapted to urge the plunger in one direction to engage and hold the jaws in selected position, a handle on the plunger and capable of limited longitudinal movement with respect thereto, said spring means being adapted to hold the handle and plunger yieldably against relative movement, said handle being adapted to be actuated to slide the plunger in the opposite direction against the action of said spring and thereby to release it from holding engagement with the jaws; and closing movement of said jaws being adapted to slide the plunger through the handle and out of holding position against action of said spring.

2. An elevator including a body, a rod encircling element pivoted on the body and swinging between open and closed positions, said elements having two parts at opposite

sides of its pivot, one of which stands in the elevator bore when the element is in open position so that it may be struck by the rod to move the element to closed position, a 5 spring pressed bolt adapted to engage and hold the element in either closed or open position, and an operating handle movable in opposite directions, bearing on the body on movement in one direction and on the 10 bolt when moved in the other direction.

3. An elevator including a body, a rod encircling element movably mounted on the

body and movable between closed and open 15 positions, a spring pressed bolt acting on the element to lock it in closed position, and a movable operating handle for retracting the bolt, said element being movable from open to locked condition without movement of the handle.

In witness that I claim the foregoing I 20 have hereunto subscribed my name this 27th day of October, 1924.

WILLIAM WEBSTER WILSON.
